Inventor

M. Oertz,

By Marshall Clark Atlys.

UNITED STATES PATENT OFFICE.

MAX OERTZ, OF HAMBURG, GERMANY, ASSIGNOR TO CAMILLO CASTIGLIONI, OF VIENNA, AUSTRIA.

FAIR-LEADER BOARD.

Application filed May 13, 1921. Serial No. 469,357.

To all whom it may concern:

Be it known that I, MAX OERTZ, residing at Hamburg, Germany, have invented certain new and useful Improvements in Fair-
5 Leader Boards, of which the following is a specification.

The otter boards which are most commonly used for bottom trawling, more particularly for deep sea fishing with bottom 10 trawling nets, consist of flat wooden plates reinforced with iron and are attached to the towing ropes through the medium of rods or chains. It has also been proposed to construct flat otter boards with tail 15 surfaces set at an angle which, however, are only able to exercise a certain amount of control over the otter board without improving its capacity for keeping the net open.

The spreading action of the otter boards 20 on the net is dependent on the size of the boards, the angle at which the towing rope acts and the towing power or towing speed. Every increase in the spreading action of 25 the otter boards may be regarded as equivalent to an improvement in the catching capacity, since, the other conditions of operation being the same, the width of the mouth of the net is more suitable and in some cases a larger net can be employed.

According to this invention the experience 30 which has been gained in aircraft construction in connection with the formation of the supporting surfaces is utilized for increasing the spreading force of the otter boards 35 which for this purpose are cambered outwardly in and lateral to the direction of towing. This new shape of the otter boards which is similar to that of aircraft supporting surfaces on the one hand enables the 40 towing force, i. e. the power of the engines, to be reduced without detrimentally affecting the catch and, with engines of the same size, makes it possible to use larger nets than hitherto and to increase the width of 45 the mouth. In the course of trials it has been established that in consequence of the new shape, the increase in the spreading power relatively to that of the flat boards hitherto used, amounts to from 40 to 49 per- 50 cent, according to the setting.

In addition to the camber in and lateral to the direction of towing, the otter board can be cambered outwardly by a slight amount in and lateral to the direction

of its height. At the same time the rear- 55 ward portion of the otter board may be made thinner, that is to say the cross section of the board may be tapered rearwardly, in order to reduce the formation of eddies at the rear edge and the resistance 60 to towing thereby set up.

The invention is illustrated by way of example in the accompanying drawings in which:—

Fig. 1 is a perspective view of one con- 65 structional form of the improved otter board,

Fig. 2 is a cross section of the otter board on line 2—2 of Fig. 1,

Fig. 3 is a vertical section on line 3—3 of 70 Fig. 1,

Fig. 4 is a vertical section on line 4—4 of Fig. 1,

Fig. 5 is a vertical cross section of a modification of the otter board slightly cambered 75 in the vertical section,

Fig. 6 shows the complete arrangement of a trawl net fitted with improved otter boards,

Fig. 7 is a side elevation of a slightly 80 modified form of an otter board,

Fig. 8 is a longitudinal section on line 8—8 of Fig. 7,

Fig. 9 is a still further modification of 85 the otter board, and

Fig. 10 is a horizontal longitudinal sec- 90 tion taken on line 10—10 in Fig. 9.

Referring to the drawing, the otter board *a* has the form of a shallow trough which is slightly cambered in and lateral to the 95 vertical direction and somewhat more cambered in and lateral to the longitudinal direction. To the inside of the camber are attached the angular rod members *b*, *c*, chains or the like. The tow rope *d* is at- 95 tached at the apices of the angles formed by rods *b*—*c*, and the net is attached to the eyes *e* and *f* on the somewhat tapered rear edge of the board. The rearwardly tapered cross section of the board is clearly shown 100 in Fig. 2 as well as the shape of the board which is fashioned like that of supporting planes of aircraft.

Modifications of the improved otter board are shown in Figures 4 to 7, in which the 105 board is constructed from pieces of uniform thickness which are rigidly connected to one another at an obtuse angle. The edges

of the board may be rounded off slightly on the outer side and the cross section of the rearward portion can be tapered for the purpose of reducing the towing resistance of the board.

If the board is to be cambered in the vertical section also, it is built up from composite pieces in this direction also. The longitudinal cross section (that is the section parallel to the direction of towing) and in some cases also the vertical cross section of boards thus constructed are bounded by bent lines, the individual sections of which constitute chords or tangents to the curves of the otter board surface. Even a board having only a single bend laid out according to this mode of construction, for instance by building up the board from a front and a rearward portion which at the angle of inclination are rigidly joined together (Figs. 7 to 10 inclusive), enables the spreading force to be increased to a considerable degree relatively to that of the hitherto known boards. Otter boards of the description can easily be built up out of the old straight otter boards which are now used.

Figures 6 and 7 show the mode of constructing an otter board out of three parts joined together in the manner above described.

It will be obvious that the parts which are joined together can be stiffened by means of battens *g* and *h*, angle irons *i* or the like, so

that the joints will be able to withstand the high stresses to which they are subjected.

Having now particularly described and ascertained the nature of my invention and in what manner the same is to be performed, I claim:-

1. An otter board, more particularly for bottom trawl nets, the section of the board being cambered outwardly in and lateral to the direction of towing in the manner of the supporting planes of aircraft. 40

2. An otter board with the section being cambered outwardly in and lateral to the direction of towing and in the manner of the supporting planes of aircraft, its thickness being decreased rearwardly. 45

3. An otter board curved in the manner of the supporting planes of aircraft being built up from pieces which are rigidly connected together at an angle in the longitudinal direction of the board so as to form a trough having the properties of aircraft 50 supporting planes.

4. An otter board curved in the manner of the supporting planes of aircraft, the traction members engaging the board at its inner concave surface. 55

In testimony whereof I affix my signature in presence of two witnesses.

MAX OERTZ.
